UNITED STATES PATENT OFFICE.

HARRY FRYMAN, OF GRIMSBY, LINCOLN, ENGLAND.

SIGNALING APPARATUS FOR VEHICLES.

1,391,623.

Specification of Letters Patent. Patented Sept. 20, 1921.

Application filed November 10, 1920. Serial No. 423,135.

(GRANTED UNDER THE PROVISIONS OF THE ACT OF MARCH 3, 1921, 41 STAT. L., 1313.)

To all whom it may concern:

Be it known that HARRY FRYMAN, a subject of the King of Great Britain and Ireland, residing at 188 Albion street, Grimsby, Lincoln, England, has invented certain new and useful Improvements in Signaling Apparatus for Vehicles, (for which he has filed an application in Great Britain May 19, 1919, Serial No. 12,513) of which the following is a specification.

This invention relates to signaling apparatus for vehicles which may be controlled by control mechanism described in the specification of my co-pending patent application Serial No. 334,742.

The object of this invention is to provide means wherein signaling indicators, arranged generally on the front and back of the vehicle, may be readily turned and locked in the desired position from a control box or device situated near the hand of the driver or operator.

The invention will now be described with reference to the accompanying drawings in which:

Figure 1 is a front view of one of the indicator arrows, Fig. 2 being a vertical section, and Fig. 3 a front view with the cover removed.

Fig. 5 is a vertical section of the arrow supporting box; Fig. 4 being a section on the line A—B looking to the left, Fig. 6 being a similar section looking to the right. Fig. 7 shows the device and indicators mounted on a car.

Referring first to the indicators and their supporting boxes as shown in Figs. 1 to 3, the indicator in this case is in the form of a hollow arrow constituted by a box 1 provided with a removable cover 2 having an opening 3 in the shape of an arrow cut out of it. This opening can be covered by a transparent plate 4 of glass, celluloid or the like. A reflector 5 is secured in the box, its upper part inclining forward in order to better receive and project the rays of an electric lamp 6 secured in the bottom of the box. The back of the box 1 and the reflector 5 may have small observation holes 7 to enable the driver to see whether the arrow is properly illuminated.

In approximately the middle of the back of the indicator is a block 8 having a projecting split lug 9, the whole being perforated and screw threaded at 8^a to receive the

end of a supporting spindle 10 (Fig. 5) the connection between the spindle and block 8 being rendered rigid by a screw 9^a (Fig. 3) drawing the ends of the lug 9 together and then binding the block securely to the spindle. 60

The lead 6^a for the lamp preferably passes through the block 8 and spindle 10, which is tubular.

The other end of this spindle is supported 65 in a cylindrical casing 11 having a removable cover 12. Secured to the bottom of the casing 11 is a plate or ring 13 having four equally distant holes or slots 14 having inclined or countersunk faces 14^a for a purpose 70 to be described.

On the spindle 10 is freely mounted a plate 15 having two oppositely arranged slots 15^a adapted to receive studs 16 projecting from the back of a plate 17 having a square opening 17^a to receive the corresponding shaped portion 10^a of the spindle 10. These studs for the portion of their length nearest to the plate 17 are conical or have inclined sides, this portion being that which 80 is normally situated in the slots 15^a as clearly shown in Fig. 5.

A double grooved pulley block 19 is supported partly on the end of the spindle 10 and partly by its reduced end 19^a engaging 85 in a circular recess or hole 12^a in the cover 12. The block 19 and plate 15 are connected by means of two rods or members 20, and are at such a distance apart as to allow the plate 17 to move back slightly along the spindle 10, against the pressure of a spring 21, one end of which is secured in the recess in the block 19, while its other end presses against the plate 17. 90

One of the circular grooves in the block 19 carries a coil spring 22 one end of which is secured to a rod 23 in the groove and the other to a pin 24 secured to the casing 11, or if the spring is arranged in the groove in the cap 12, its outer end will be pinned to the 100 cap. Thus if the block is rotated by a Bowden wire in a clockwise direction as seen in Fig. 6 against the action of the spring 22, the latter will always tend to return it in an anti-clockwise direction when the pull of the 105 wire is released to a degree corresponding to the amount of wire released.

In the other groove I arrange a short length of chain 25 (Fig. 6) one end being secured to a rod 26 in the groove and the 110

other end passing out of the casing 11 through a hole 11^a and into a tubular guide 11^b secured thereto. The other end of the chain is connected by means of an adjusting screw 26^b to the end of a Bowden wire 26^a or similar device which passes to the control handle or wheel 27 which as hereinbefore stated is preferably of the kind described in the specification of my co-pending patent application Serial Number 133742.

It will be seen that if the chain 25 is drawn down by the operation of the Bowden wire the block 19 will be given a rotary motion, and, as it is connected to the plate 15, in so doing the edges of the slots 15^a on the plate 15 will bear against the inclined sides of the studs 14, and cause the studs to be partially moved backward and out of the lower portion of the slots 14 in the plate 13, which upon then had locked the studs and thereby the whole device within the casing against rotation. The studs now ride up upon the countersunk openings of the slots 14 thus completing the unlocking of the device.

Consequently, the block and studs carrying plate will be rotated to a quarter or a half revolution in an anticlockwise direction or a quarter revolution in a clockwise direction in accordance with the movement of the Bowden wire. Owing to the square portion 10^a of the spindle, the latter will also be rotated, and thus the indicator arrow will be turned through a quarter or a half revolution in anticlockwise direction, or a quarter revolution in a clockwise direction.

Normally the arrow points upward indicating that the vehicle is going straight ahead, if turned to the driver's right by the agency of spring 22 upon release of the Bowden wire through 90° so as to point horizontally to the right it indicates that the driver is about to turn to the right, if turned through 180° the arrow points downward, indicating stopping or slowing up, while if turned to the driver's left by the agency of the Bowden wire 26^a through 90° it points horizontally to the left indicating a left hand turn is about to be made.

It will be seen that the interposition of the plate 17 with its studs, between the block 19 and the shaft 10 allows the pointer to be readily turned to any desired position by means of the Bowden wire control but the pointer cannot be turned by hand from the outside, since on any such attempt being made the studs 16 will engage against the flat sides of the holes 14 in the plate 13, whereby any turning movement is prevented. When, however, 180° rotation of the arrow is effected through the agency of the plate 15 either by the Bowden wire 26^a or by the coil spring 22, the studs 16 will engage with the next hole to come into register, but owing to the cam action of the inclined sides of the studs and of the plate 15,

the studs will be immediately disengaged again, so that the rotation is not interrupted.

In the drawings the casing 11 is shown as supported on a U shaped bracket which can be secured to any suitable part of the vehicle.

It should be noted that there is no constructional difference between the front arrow box and the rear arrow box except that their respective operating chains are secured to the blocks 19 at points which are 90° apart with regard to one another.

If the arrow boxes were turned so as to both face in one direction the arrangement of the parts of each would be seen to be identical (except the points of fixation of the chains to the wheels)—springs wound the same way, and the chains leading off the same way. If the arrows are now operated by the control box it will be seen that a turn can be made in opposite directions since the chain of one is pulled while that of the other is released. Hence it will be understood that when the arrows face in opposite directions, as when mounted one on the front and one on the rear of a car they will always give identical signals.

What I claim as my invention is:

1. Signaling apparatus for vehicles comprising indicators mounted on spindles at the front and rear of the vehicle, and operated from the control handle or wheel within reach of the driver, so that on turning the control handle the indicators will be correspondingly moved to the desired signaling position and a locking device for the indicator spindle to prevent movement of the indicator from one signaling position to another except by operation of the control device.

2. Signaling apparatus for vehicles comprising indicators mounted on spindles at the front and rear of the vehicle, and operated from the control handle or wheel within reach of the driver, so that on turning the control handle the indicators will be correspondingly moved to the desired signaling position and locking means comprising a fixed disk with bevel edged holes or slots and a spring pressed plate with beveled edged studs adapted to engage said holes or slots, said plate being longitudinally movable along and rotatable with the spindle carrying the indicator.

3. Signaling apparatus for vehicles comprising indicators mounted on spindles at the front and rear of the vehicle, and operated from the control handle or wheel within reach of the driver, so that on turning the control handle the indicators will be correspondingly moved to the desired signaling position, locking means comprising a fixed disk with bevel edged holes or slots and a spring pressed plate with beveled edged studs adapted to engage said holes

or slots, said plate being longitudinally movable along and rotatable with the spindle carrying the indicator, a spring influenced member adapted to be rotated from the control device having diametrically arranged members projecting from said spring influenced member passing through the stud carrying plate and a slotted plate surrounding intermediate portions of the 10 studs adapted to be engaged by the aforesaid diametrically disposed members in such a manner that the slotted plate in turning with the aforesaid spring influenced member carries the studs and its supporting 15 plates from one locking position to another.

4. Signaling apparatus for vehicles comprising indicators mounted on spindles at the front and rear of the vehicle, and operated from the control handle or wheel with- 20 in reach of the driver, so that on turning the control handle the indicators will be

correspondingly moved to the desired signaling positions, locking means comprising a fixed disk with beveled edged holes or slots a spring pressed plate with beveled 25 edged studs adapted to engage said holes or slots, said plate being longitudinally movable along and rotatable with the spindle carrying the indicator, a rotatable tubular member receiving one end of the spindle 30 of the indicator, a coiled spring adapted to return it to its normal position after it has been rotated and a chain or the like encircling said tubular member and having one end fast therein and the other end connected 35 to the flexible transmission means.

In testimony whereof he affixes his signature in presence of two witnesses.

HARRY FRYMAN.
